CATTLE MARKER

William F. Schacht, Huntington, Ind.

Application August 22, 1941, Serial No. 407,968

9 Claims. (Cl. 40—3)

This invention is a novel improvement in cattle markers adapted to be readily applied either as horn chain markers or neck chain markers to cattle or live-stock so that farmers, herdsmen or breeders can readily distinguish or identify same.

The present invention is an improvement upon the markers disclosed in my copending application Serial No. 389,984, filed April 23, 1941 in which the markers comprise a one-piece marker plate of simple construction, and made of any suitable material such as brass, or steel which may be chrome-plated or brass-plated, and bearing appropriate identification indicia, said plate having a shank at the upper edge of the plate, which shank may be single but is preferably split, the members of the shank being bent back upon themselves to form integral eyes, a link at one end of the chain being secured in one said eye, and the other eye being left partially open so that in applying the marker it was only necessary to pass the chain around the neck or horns of the live-stock and to engage a link adjacent the free end of the chain in said open eye, thereafter applying sufficient pressure to close the open eye thus locking the ends of the chain around the neck or horns of the animal to prevent ready removal therefrom.

I have found, from practical experience, that the animals often rub their horns and heads together tangling or locking the chains together, or catch the chains in fences or the like, and the pull on the chain caused by attempts to free same opens one or both eyes whereby the marker becomes detached and lost. In order to prevent such loss, I have provided the marker plates with novel means for preventing the chain links from slipping out of eyes which are not fully closed, also means for preventing twisting or bending of the eyes, and also means for preventing opening of the eyes.

One object therefore of my invention is to provide a marker of the above type with raised lips or offset portions formed in the material of the shanks adjacent the outer ends of each shank so that when the shanks are bent or rolled over to form the eyes the raised lips or projections will project inwardly of the eyes adjacent the split and effectively prevent the link of the chain which is engaged in said eye from readily slipping out if the eye is not fully closed.

Another object is to provide novel means for preventing the outer ends of the shanks from spreading laterally of the eyes due to opposed strains on the opposite ends of the chain, said means consisting of flanges on the plate engag-

ing the outer edges of the shanks of the eyes adjacent the split, or consisting of flattened rings adapted to embrace both eyes and mounted on the outer portions of the shank members thereof adjacent the splits.

Still another object of the invention is to provide novel means for preventing opening of the eyes due to pull on the chain consisting of raised projections or shoulders at the bases of the shank members of the eyes upon which the outer ends of the shanks seat when the shanks are rolled to form the eyes, said raised projections being formed by offsetting ridges or grooves in the material of the marker plate itself at the bases of the shank members.

Other minor objects of the invention will be hereinafter set forth.

I will explain the invention with reference to the accompanying drawings, which illustrate several practical embodiments thereof to enable others to adopt and use the same; and will summarize in the claims the novel features of construction, and novel combinations of parts, for which protection is desired.

In said drawings:

Fig. 1 is a view showing my novel chain marker applied to the horns of a cow.

Fig. 2 is a view showing the chain marker applied around the neck of a cow.

Fig. 3 is an enlarged plan view of a blank from which the marker plate is made.

Fig. 4 is a side elevation of the chain marker shown in Fig. 3 after the shank members have been rolled to form eyes.

Fig. 5 is a plan view of a blank for a modified marker plate.

Fig. 6 is a side elevation of the marker shown in Fig. 5 after the shank members have been rolled to form eyes.

Fig. 7 is a perspective view of the finished marker plate formed from the blank shown in Fig. 5, said view showing one end of the chain locked in one closed eye of the marker plate, the other eye being open to receive a link at the other end of the chain.

Fig. 8 is a plan view of a further modified blank.

Fig. 9 is a side elevation of a marker formed from the blank shown in Fig. 8.

Fig. 10 is a plan view of a still further modified blank.

Fig. 11 is a side elevation of one form of finished marker formed from the blank shown in Fig. 10.

Fig. 12 is a side elevation of another form of

finished marker formed from the blank shown in Fig. 10.

Fig. 13 is a plan view of a further modified form of blank having a strap for preventing spreading of the eyes, said view showing one end of the chain and the link engaged in one closed eye, the other eye being open to receive a link at the other end of the chain, and the strap.

Fig. 14 is a plan view of the marker shown in Fig. 13 when locked upon the horns or neck of the animal.

Fig. 15 is a plan view of a further modified marker with a ring in the pair of eyes.

Fig. 16 is a plan view of a still further modified form of marker.

My novel marker may be formed from sheet metal blank such as shown in Fig. 3, same comprising a plate portion 1a, and an integral shank portion 1b extending from the top edge thereof, shank portion 1b being of substantial length and having spaced tongues 1c of substantial width adapted to be bent or rolled back as shown in Fig. 4 to form a pair of spaced eyes, the common axis of which is disposed parallel with the plane of the plate. Each eye is adapted to receive an end of a chain 2 which is passed around the horns of the animal (Fig. 1) or around the neck of the animal (Fig. 2), the marker plate securing the ends of the chain together. The spacing between the eyes is sufficient to prevent interference between the adjacent ends of chain 2 when engaged therewith.

At the outer ends of tongues 1c are knobs 1d, preferably formed by offsetting under pressure the material of the tongues but may be formed in any other desired manner. Said knobs 1d provide bulges on the tongues which project inwardly within the eyes adjacent the splits, or points of contact of the outer tips of the tongues with the shanks 1b, when the tongues and shank are rolled to form the eyes, the knobs 1d serving to prevent the links of chain 2 from readily slipping out of the eyes in event the eyes become partially opened or are not fully closed initially, the chain resting in front of knob 1d as indicated at 2x (Fig. 4) when the eye starts to open, or the knob 1d presenting a longer slot through which the chain link must slip in passing through a partly opened eye.

The marker shown in Figs. 3 and 4 would preferably be made up with one eye of the pair closed tightly to lock the engaged link at one end of chain 2 therein, while the other eye of the pair would be left partially open (as illustrated in Figs. 7 and 13) so that in applying the marker to the cattle the farmer or herdsman need only insert a link adjacent the free end of the chain in said open eye and to thereafter apply sufficient pressure to close the open eye, whereby both ends of the chain which passes around the horns or neck of the live-stock will be locked to the marker plate 1a.

By the above construction, a one-piece marker is provided of inexpensive construction which may be readily applied by a farmer or herdsman around the neck or horns of a cow or other animal. The provision of two closely adjacent eyes 1e receiving the ends of the chain 2 or 3 provides a marker in which the plate portion 1a of the marker, which bears the proper identification number or indicia for the respective cow or live-stock, will lie flat upon the forehead of the cow as shown in Fig. 1, or will be held exposed to front view when the marker is used as a neck

chain marker as shown in Fig. 2 since the two spaced eyes tend to prevent the adjacent ends of the chain from twisting together.

As the animal grows, it will become necessary for the farmer or herdsman to pry open one eye of the marker and engage a different link of the chain 2 in said opened eye, and then again close the said eye to lock said link therein, thus permitting the overall length of the chain to be elongated to correspond with the growth of the live-stock.

In actual practice it has been found that the eyes of such markers may become separated in an axial direction whenever the cattle to which the markers are applied get the chains caught due to locking horns or grazing too near fences or other fixed objects, the strain on the chain tending to pull the eyes apart along their common axis thereby partially opening the eyes. To prevent such spreading I provide a modified form of marker plate shown in Figs. 5, 6 and 7, in which the body 1a is provided with the shank 1b and the pair of spaced tongues 1c, the outer ends of which may be provided with the knobs 1d in the same manner as above described in connection with Figs. 3 and 4. In Figs. 5, 6 and 7, however, the body is made somewhat wider adjacent its upper end and the sides of the marker plate 1a are bent or flanged outwardly along the dot and dash lines 1e (Fig. 5) to form flanges 1f adapted to contact the outer side edges of tongues 1c when rolled to form eyes as shown in Figs. 6 and 7, the split in the eyes terminating within the lengths of the flanges 1f. In this modification the upper ends of the flanges 1f further serve to prevent the chain links from passing out of the eyes in event the eyes should accidentally become partly opened and the flanges greatly reinforce the eyes and prevent spreading along their common axis.

Instead of the flanges 1f, shown in Figs. 5 to 7, a strap 3 may be used as shown in Figs. 13 and 14, which strap is of length substantially equal to the overall width of the pair of eyes. One end of the strap 3 and one end of chain 2 may be initially locked as shown in Fig. 13 in one eye of the pair, or permanently secured therein at the time the marker is made. The other eye of the pair may be left open, so that in applying the marker to the live-stock the farmer or herdsman need merely to run the chain around the horns or neck of the animal and to engage a link adjacent the free end of the marker into the open end and to then engage the other end of the strap 3 in the open eye and then close the open eye as shown in Fig. 14, the strap 3 being disposed and maintained on the rolled tongues 1c adjacent their outer ends, and thus preventing the outer ends of the eyes adjacent the split from separating along their common axis.

In practice it is often found that the eyes of the marker plate tend to expand and open under tension applied to the chain 2, and I therefore provide novel preventing means one form of which is shown in Figs. 8 and 9, in which the shank 1b of marker plate 1a is provided with spaced bulges 1g disposed opposite the centers of the tongues 1c and extending outwardly on the shank into position to underlie the outer ends of the rolled tongues 1c, as clearly indicated in Fig. 9, thus forming shoulders upon which the outer ends of the tongues rest to resist opening or expansion of the eyes. Preferably bulges 1g are pressed and offset from the body of the shank 1b itself, but may be otherwise formed in any de-

sired manner, or may comprise rivet heads or other means applied to the shank $1b$ for such purpose.

Modifications of the means for preventing ready opening or expansion of the eyes are shown in Figs. 10, 11 and 12 in which the body $1a$ is provided with an integral shank $1b$. Instead of the bulges $1g$ shown in the shank $1a$ in Figs. 8 and 9, a transverse recess or rib may be provided extending across the shank adjacent the inner end thereof. Fig. 11 shows the use of a transverse recess $1h$ pressed from the material of the shank itself, of such width as to receive the outer ends of the tongues $1c$ when rolled to form the eyes, the lower wall of the recess forming a shoulder upon which rest the outer tips of the rolled tongues $1c$. Fig. 12 indicates the use of a transverse rib $1k$, in place of groove $1h$ shown in Fig. 11, the rib $1k$ being pressed from the shank $1b$ and extending across the full width of the shank adjacent the lower end thereof and forming a shoulder upon which the outer tips of the tongues $1c$ rest when the tongues are rolled to form the eyes.

If desired, a ring 4 , Figs. 15 and 16 may be used with the marker plates, the eyes engaging the ring, and a chain or strap being slipped through the ring and secured around the neck of a young animal, and the ends of the chain or strap secured together in any desired manner, such as by a padlock or by tying. Later, when the animal grows, the ring 4 may be removed from the eyes of the plate and the ends of chain 2 inserted and locked therein as previously described. The plate $1a$ (Figs. 15 and 16) may be provided with any of the features, such as flanges $1f$, bulges $1g$, ribs $1k$, or grooves $1h$ described in the preceding figures.

In Fig. 16 a single relatively broad and heavy eye $1c$ is used instead of a pair of spaced eyes as in Fig. 15, and the single eye is twisted with respect to the plane of plate $1a$ so that the marker may be read from the front of the animal rather than from the side, otherwise the marker in Fig. 16 may be used similarly to that shown in Fig. 15. However, the use of two eyes, as shown in Fig. 15, rather than a single eye (Fig. 16) provides a double lock for the ring 4 , and is therefore preferable to use.

I do not limit my invention to the exact forms shown in the drawings, for obviously changes may be made therein within the scope of the claims.

I claim:

1. An animal marker or the like, comprising a relatively rigid indicia bearing plate provided with an integral shank extending from its upper edge and rolled to form a closed eye, said eye being openable upon application of relatively heavy stress, an offset portion extending inwardly of the eye at the outer end of the shank; and a shoulder on the base of the shank underlying the outer end of the rolled shank and upon which the said outer end seats.

2. An animal marker or the like, comprising a relatively rigid indicia bearing plate, an integral shank extending from the upper edge of said plate; a spaced pair of tongues extending from the outer edge of said shank; said shank and tongues being rolled to form spaced eyes having their common axis disposed parallel with the plane of the plate; each said eye being openable upon application of relatively heavy stress, an offset portion extending inwardly of each eye at the outer end of each tongue; a chain having one end engaged in one eye, said eye being closed; and the other eye being open and adapted to receive a

link adjacent the outer end of the chain before closing of said eye.

3. An animal marker or the like, comprising a relatively rigid indicia bearing plate; an integral shank extending from the upper edge of said plate; a spaced pair of tongues extending from the outer edge of said shank; said shank and tongues being rolled to form spaced eyes having their common axis disposed parallel with the plane of the plate; each said eye being openable upon application of relatively heavy stress; an offset portion extending inwardly of each eye at the outer end of each tongue; and a shoulder on the base of the shank underlying and forming a seat for the outer end of each rolled tongue; said shoulder comprising a transverse rib pressed outwardly from the material of the shank.

4. An animal marker or the like, comprising a relatively rigid indicia bearing plate; an integral shank extending from the upper edge of said plate; a spaced pair of tongues extending from the outer edge of said shank; said shank and tongues being rolled to form spaced eyes having their common axis disposed parallel with the plane of the plate; each said eye being openable upon application of relatively heavy stress; an offset portion extending inwardly of each eye at the outer end of each tongue; and a shoulder on the base of the shank underlying and forming a seat for the outer end of each rolled tongue; said shoulder comprising a transverse groove pressed inwardly from the material of the shank.

5. An animal marker or the like, comprising a relatively rigid indicia bearing plate; an integral shank extending from the upper edge of said plate; a spaced pair of tongues extending from the outer edge of said shank; said shank and tongues being rolled to form spaced eyes having their common axis disposed parallel with the plane of the plate; each said eye being openable upon application of relatively heavy stress; an offset portion extending inwardly of each eye at the outer end of each tongue; and a shoulder on the base of the shank underlying and forming a seat for the outer end of each rolled tongue; a chain having one end engaged in one eye, said eye being closed; and the other eye being open and adapted to receive a link adjacent the outer end of the chain before closing of said eye.

6. An animal marker or the like, comprising an indicia bearing plate provided with a relatively rigid shank extending from its upper edge and rolled to form a closed eye, and a shoulder on the base of the shank underlying the outer end of the rolled shank and upon which the said outer end seats.

7. An animal marker or the like, comprising an indicia bearing plate, a relatively rigid integral shank extending from the upper edge of the plate, a spaced pair of tongues extending from the outer edge of said shank, said shank and tongues being rolled to form spaced eyes having their common axis disposed parallel with the plane of the plate, a shoulder on the base of the shank underlying and forming a seat for the outer end of each rolled tongue, said shoulder comprising a transverse rib pressed outwardly from the material of the shank.

8. An animal marker or the like, comprising an indicia bearing plate, a relatively rigid integral shank extending from the upper edge of the plate, a spaced pair of tongues extending from the outer edge of said shank, said shank and tongues being rolled to form spaced eyes having their common axis disposed parallel with the plane of the plate, a shoulder on the base of the shank underlying

and forming a seat for the outer end of each rolled tongue, said shoulder comprising a transverse groove pressed inwardly from the material of the shank.

9. An animal marker or the like, comprising an indicia bearing plate, a relatively rigid integral shank extending from the upper edge of the plate, a spaced pair of tongues extending from the outer edge of said shank, said shank and tongues being rolled to form spaced eyes having their common

axis disposed parallel with the plane of the plate, a shoulder on the base of the shank underlying and forming a seat for the outer end of each rolled tongue, a chain having one end engaged in one eye, said eye being closed; and the other eye being open and adapted to receive a link adjacent the outer end of the chain before closing of said eye.

WILLIAM F. SCHACHT.
